[57] CLAIM

The ornamental design for a solar voltaic generator, as shown and described.

DESCRIPTION

FIG. 1 is a top left perspective view of a solar voltaic generator showing my new design;

FIG. 2 is a left side elevation thereof, the opposite side being substantially similar;

FIG. 3 is a front perspective thereof taken slightly left from center;

FIG. 4 is a front elevation thereof, seen from an angle of about 45 degrees from the horizontal; and

FIG. 5 is a rear elevation thereof taken slightly right from center.

FIG. 1

FIG. 2

FIG. 3

FIG. 4

FIG. 5
